(57) **CLAIM**

The ornamental design for a fluorescent light socket, as shown and described.

DESCRIPTION

FIG. 1 is a front view of the design according to the invention.

FIG. 2 is a rear view of the design according to the invention.

FIG. 3 is a top view of the design according to the invention.

FIG. 4 is a bottom view of the design according to the invention.

FIG. 5 is a left side view of the design according to the invention.

FIG. 6 is a right side view of the design according to the invention.

FIG. 7 is a cross-sectional view of the design cut across the line 7—7 of FIG. 1.

FIG. 8 is a bottom and left front perspective view of the design in use according to the invention; and,

FIG. 9 is a perspective view of the design in use according to the invention. The broken line portions of FIG. 9 are for illustrative purposes only and form no part of the claimed design.
